UNITED STATES PATENT OFFICE.

JAMES BOLTON, OF CHICAGO, ILLINOIS.

SEWING-MACHINE.

SPECIFICATION forming part of Letters Patent No. 470,281, dated March 8, 1892.

Application filed July 19, 1890. Serial No. 359,279. (No model.)

To all whom it may concern:

Be it known that I, JAMES BOLTON, a citizen of the United States, residing at Chicago, in the county of Cook and State of Illinois, have invented certain new and useful Improvements in Sewing-Machines, of which the following is a specification, reference being had therein to the accompanying drawings.

My invention has for its object to provide a lock-stitch sewing-machine which is simple in construction, so that it may be cheaply manufactured, and which, while light-running, is strong and positive in operation, so that it is capable of high rates of speed.

15 In the drawings, Figure 1 is a sectional side elevation of my improved machine. Fig. 2 is a bottom view thereof. Figs. 3, 4, and 5 are sections on lines 33, 44, and 55, respectively, of Fig. 1, looking in the directions of the arrows adjacent to said lines. Fig. 6 is a front end view of my machine. Figs. 7, 8, and 9 are detail views of the shuttle mechanism, and Fig. 10 is a detail view of the shuttle.

20 A denotes the work-plate, B the bracket-arm, and C the driving-shaft journaled in the upper portion of said arm and provided near its rear end with the crank c for operating the feed and shuttle mechanisms and at its forward end with a crank-disk c', having a crank-pin c², entering an ordinary heart-cam d, attached to the needle-bar D.

25 The bed-plate is provided on its underside with suitable brackets a, through which are tapped center screws a', serving as pivots for the shuttle and feed-operating rock-shafts E and F. The crank c is connected by a pitman C' with the rear arm f' of the rock-shaft F, said shaft carrying near its forward end an arm or segment f², provided with a cam-groove f³ and also with a rib f, extending at a right angle from said segment, and to which rib the shuttle-driver g is pivotally attached by a screw or pin g', the shuttle-driver having a horn g² to enter a recess near the 30 nose of the shuttle H and a lip or flange g³, which abuts against the heel of the shuttle. The vertical shuttle-race h is on the inner face of the web a², cast on the bed-plate, and is cut into said web, so as to form a projecting or overhanging lip h', Fig. 1, against which fits a segmental flange h², Fig. 10, formed on the outer or face side of the shut-

tle and curved to correspond to the curvature of the shuttle-race. It will be observed that the shuttle-driver stands up vertically, so that the centrifugal pressure of the shuttle against the overhanging lip h' of the shuttle-race is counteracted by gravity or the weight of the shuttle, and thus the friction of the shuttle against the shuttle-race is reduced to a minimum and little or no oil will therefore be required to lubricate the shuttle in its race. It will also be obvious that the shuttle vibrates in the arc of a comparatively small circle, so that its motion is a smooth and easy one, thereby avoiding the vibratory jar incidental to long shuttle-carrying levers and adapting my machine to high rates of speed. The shuttle is loosely held between the horn g² and the lip or flange g³ of the driver and the race h, and also between the floor of the driver and the overhanging lip h' of the shuttle-race, the said lip co-operating in connection with the curved flange h² on the shuttle to prevent the latter from rising in the race, as 75 will be obvious.

30 The shuttle H has a straight lower face and a curved upper face or edge which is the true arc of the circle in which the said shuttle vibrates, the straight lower face meeting the curved upper face at the point of the shuttle, so that the said point is close up against the shuttle-race and can thus take the loops of needle-thread without requiring the needle to descend as low as would otherwise be necessary, and thus a comparatively short needle may be employed. In other words, my shuttle is what is known as a "high-pointed" one.

35 Owing to the fact that the shuttle-driver is pivotally attached to the rib f of the segment f² by the screw or pin g', the said driver may be turned slightly on the pin or screw by the operator when the shuttle is at its extreme forward position, as indicated by Fig. 7, with its nose slightly below the lower forward end 40 of the shuttle-race. This slight turning of the shuttle-driver by the finger of the operator on said screw or pin clears the heel of the shuttle from the lip h of the shuttle-race, as shown in Fig. 8, and when the shuttle-driver is thus turned the shuttle may readily be removed from or inserted in the driver. When the driver starts on its backward movement after the shuttle has been placed therein,

the contact of the vertical front face of the shuttle with the vertical face of the shuttle-race swings the driver back to its normal position, in which it will at all times remain 5 during the operation of the machine.

To cheapen the construction of my machine, as well as to avoid the friction incidental to the use of a cam-operated or lever take-up, I prefer to use in connection with 10 my vertically-operated vibrating shuttle a needle-bar take-up. To this end I have attached to the heart-cam d , by which the needle-bar is operated, a plate i , having two slotted thread-eyes i' extending outward through 15 slots k in the face-plate K . On the face-plate between the said slots k is a stationary cam or projection m , formed in the present instance by making a V-bend in a plate m' , which is attached to the face-plate by a screw 20 k^2 . The upper end of the plate m' is turned over and downward to form the hook m^2 , beneath which is housed the upper end of a retaining-spring n , also secured in place by the screw k^2 . The retaining-spring n presses 25 against the plate m' at its upper end above the projection m only, and is properly bent, so as to leave a thread-space between itself and the said plate m' , excepting above said projection.

30 With the usual throw to a needle-bar having a take-up thereon sufficient lift would not be given to the thread to clear it from the heel of the vertically-vibrating shuttle before the latter quite completes its forward 35 movement. It is for this reason that the cam or projection m , over which the thread is drawn by the thread-eyes i' , is required, the said projection taking up sufficient slack during the early part of the upward movement 40 of the needle-bar to draw the loop of needle-thread away from the heel of the shuttle when the latter is in the forwardly-moving position shown by Fig. 3 and before the forward movement of the shuttle is quite completed. It is necessary to clear the loop of 45 needle-thread from the heel of the shuttle before the latter is far enough forward to draw its own thread taut, for the reason that as soon as the shuttle-thread is drawn taut the 50 shuttle is pulled back against the rear flange g^3 of the driver, and if the loop of needle-thread has not escaped from the shuttle before this occurs the needle-thread is liable to be broken. In other words, the said cam or 55 projection m gives the needle-bar take-up the right timing to properly draw up the slack of the loops of needle-thread passing around my vertically-vibrating shuttle, and therefore has a peculiar co-operation therewith. When the 60 needle-bar descends, the thread-retaining spring n , pressing on the plate m' , holds the needle-thread up, so that it will draw through the eye of the needle until the said eye enters the work, when the friction on the thread 65 will be sufficient to draw the thread from beneath the light pressure of the thread-retaining spring, thus permitting the needle to

draw down sufficient thread to properly form the loop for the shuttle in the usual manner.

Pivoted at a^3 to one of the brackets a is a 70 rocker J , provided with a curved slot j , said rocker being pivotally connected at o with a link o' , jointed at o^3 to the pitman C' . The rock-shaft E is provided near its rear end with an arm e , to which is jointed a link p , 75 the free end p' of which is jointed to a block p^2 , fitting in the slot j of the rocker J , said link being provided near its middle with a slot p^3 , into which extends a pin q , carried by a bell-crank feed-regulating lever Q , pivoted 80 to a rib on the under side of the work-plate. By means of the said regulating-lever the free end of said link p may be raised or lowered to bring its pivotal connection with the rocker nearer to or farther from the pivotal point a^3 of the said rocker to vary the rocking 85 movements of the shaft E . The feed-bar R is jointed to the arm e' at the forward end of the shaft E , and thus the throw of the feed-dog is governed by the extent of the rocking 90 movements of said shaft. The feed-bar is raised and lowered positively by the cam on the arm or segment f^2 of the shuttle-operating rock-shaft F , said feed-bar having a roller-stud extending into the groove f^3 of said cam. 95

The feeding mechanism just above described is not herein claimed, being embraced by my application, Serial No. 359,280, filed simultaneously herewith.

I claim—

1. In a sewing-machine, the combination, with a bracket-arm and work-plate, the latter provided with a vertical shuttle-race h , having an overhanging or horizontal lip h' of the main shaft journaled in said bracket-arm and having the crank c , the needle-bar operated by said shaft, the longitudinal rock-shaft F below the work-plate and having the arm f' at its rear end and the arm or segment f^2 near its forward end, the pitman connecting said 105 main shaft with said rock-shaft, the shuttle-driver carried by said arm or segment f^2 , and the vertically-vibrating shuttle fitting loosely between said driver and the said overhanging or horizontal lip h' , said shuttle having the 110 curved flange h^2 , fitting beneath said lip.

2. In a sewing-machine, the combination, with the needle-bar and its operating mechanism, of the longitudinal rock-shaft F , provided with the vertical segment f^2 near its 115 forward end, said segment having the rib f extending at a right angle therefrom, the shuttle-driver g , pivotally attached to said rib and having the horn g^2 and flange g^3 , the curved vertical shuttle-race h , having the horizontal or overhanging lip h' , a shuttle having a curved 120 upper portion loosely fitting beneath said lip, said shuttle-race terminating above or rearward of the point of the shuttle when the latter is at its extreme forward position to permit the pivoted shuttle-driver to be turned slightly for the purpose of enabling the shuttle to be inserted in or removed from the said 125 driver.

3. In a sewing-machine, the combination, with the needle-bar and its operating mechanism, of the rock-shaft F and means for actuating it, the vertically-vibrating shuttle operated by said rock-shaft, the take-up eyes moving with said needle-bar, the face-plate having the take-up cam or projection m, the retaining-spring n, loosely overlying said cam or projection, but bearing against a co-operating friction-surface above the latter, where-
by the needle-thread will be drawn from the

heel of the shuttle before the latter quite completes its forward movement, and whereby, also, the said thread will be held up by said spring until the eye of the needle enters the 15 work and will then be released.

In testimony whereof I affix my signature in presence of two witnesses.

JAMES BOLTON.
